ABSTRACT OF THE DISCLOSURE

Apparatus and method for the electrolytic treatment of sewage is disclosed. According to the method, electrolytic treatment of a stream in a sewage treatment plant is provided at one or more selected locations. Thus, in an otherwise generally conventional sewage treatment facility employing various well-known techniques for the removal of solids and also well-known techniques for the bacteriological digestion of contained organic materials, the method contemplates the electrolytic treatment of the final effluent stream for the purpose of disinfection thereof. In addition, in systems wherein anaerobic digesters are employed to treat the sludge from primary settlers, electrolytic treatment of the digester supernatant is provided for the purpose of destroying its putrescent odor, improving its settleability and color, and reducing its BOD and COD. The apparatus employed includes one or more electrolytic assemblies employing anodes formed of a coating of lead dioxide on a substrate of graphite or titanium, and preferably includes a hollow, cylindrical metal tube which forms the cathode and with the anode contained therein and in the form of a cylindrical member whose outer surface is equidistantly spaced from the inner surface of the cathode can. Electrolyte flows through the assembly from an inlet conduit near the bottom to an outlet conduit near the top, and electrical connections are made to the exterior cathode can and to a portion of the anode substrate which protrudes from the top of the assembly.

BACKGROUND OF THE INVENTION

The subject of ecology is one of the foremost issues of the day, not only in the United States but throughout the world. Governmental bodies and industry are discovering that people everywhere are intensely interested in cleaning up the environment and in stopping the continuing pollution of rivers, streams, lakes, and oceans. It is now well-known that one of the greatest abuses of man's environment is the discharge of inadequately treated sewage from municipalities and industries into the very sources of water from which man must draw his essential water needs. Even in the United States, which is reputed to have what may be the highest standard of living in the world, many hundreds of communities discharge their sewage directly into the nearest available body of water without any treatment whatsoever. In hundreds of other instances, the only treatment provided for sewage is to remove the largest solid matter which can be conveniently removed in settling tanks, but no other treatment is provided, with the result that a grossly contaminated effluent is discharged into the most conveniently available body of water. Even in instances where secondary treatment of the effluent is provided, the resulting discharge from the system may be badly contaminated, particularly in instances where storm sewers are not separate from sanitary sewers with the result that the sewage plant becomes greatly overloaded in the event of a heavy runoff of surface water.

The problem is greatly compounded by the growth of

2

population, particularly in urban areas whose facilities for the treatment of sewage cannot keep pace with the growth in demand. The cost of building sewage treatment facilities where none now exist, the expansion of facilities whose capacity has been exceeded, and the improvement of existing facilities which do not provide adequate treatment of the sewage so as to provide a safe effluent requires the expenditure of vast sums of money, amounting to many billions of dollars, and it is already evident that the urgent and immediate needs will not be met. This recognition that immense resources must be devoted to providing a solution to a critical problem coupled with the knowledge that such resources will not in many instances be available to the extent required, has generated intense interest in finding ways in which existing techniques for the treatment of sewage can be improved so that needed facilities can be provided at lesser cost than heretofore contemplated and also in order that existing facilities can be improved so as to increase their effective capacity, thereby making it possible for an existing sewage system to discharge a safe effluent even though the facility is now required to treat an amount of sewage greatly in excess of its design capacity.

SUMMARY OF THE INVENTION

The method and apparatus of this invention has been put to use and has been found to fulfill the foregoing requirements, i.e. by making possible the construction of a sewage plant of a predetermined capacity at lower cost than previously contemplated and the modification of existing plants so as to increase their effective capacity by a substantial degree. Described briefly, the method and apparatus of this invention comprises the judicious application, at certain strategic locations in a sewage treatment plant, of electrolytic treatment of a portion or all of the stream. This concept is to be distinguished from prior attempts at electrolytic treatment of sewage wherein it was sought to provide substantially the entire treatment of sewage, from the raw state to a final effluent meeting prescribed standards, via electrolytic treatment. It has been found that such a goal is an unrealistic one, at least for large plants which must be capable of treating hundreds of thousands or even many millions of gallons of sewage per day. Thus, the capital cost and also the operating cost of such an installation is so high as to become prohibitive. Moreover, in many of the prior art systems of electrolytic sewage treatment, it was found that the anodes available for this purpose were entirely unsatisfactory, requiring frequent replacement and being moreover generally quite inefficient.

By means of the present invention, in contrast, it has been found to be entirely practical both from the standpoint of capital cost and operating cost, as related to the surprising improvement in results, to provide several installations in a single plant where electrolytic treatment of all or a portion of the stream takes place to supplement the customary sewage treatment methods.

One highly advantageous location for electrolytic treatment is in the treatment of the supernatant from the anaerobic digesters. As is well known, such anaerobic digesters are often employed, and their function is to treat the sludge which is drawn from the primary settling tanks. The sludge, a great proportion of which is water, is pumped to digester tanks and circulated through such tanks for a period of as much as four weeks, under conditions which favor the growth of bacteria which, in effect, digest the organic matter in the sludge. The supernatant discharge from such digesters is ordinarily caused to flow back to the primary settling tanks, while the sludge which accumulates at the bottom of the digesters is periodically removed and separately processed or buried.

In a system employing such anaerobic digesters, it may be said that such digesters in effect constitute a bottleneck in the system. Thus, the proper operation of the entire system depends upon the ability of the digesters to oxidize the dissolved and colloidal organic materials in the sludge; however, when the system becomes overloaded, the flow through the digesters becomes too great to permit the proper digesting action to occur, with the result that an inadequately treated supernatant flows back into the system. When this occurs, one of the principal undesired effects is the generation of foul odors in the vicinity of the plant, causing great annoyance to the local population, particularly those residing downwind from the plant's location. As will be explained in greater detail subsequently, we have found that even a relatively slight amount of electrolytic treatment of the supernatant from the digesters with the apparatus of this invention results in complete elimination of the noisome odors. This not only puts an end to complaints from the surrounding population but also makes it possible for the supernatant to be subjected to various kinds of treatment under conditions of overload which would not otherwise be possible. For example, it then becomes feasible to pump the supernatant to a lagoon or the like in order to permit additional solids to settle out of the supernatant. Such settling out of solids is, we have found, greatly facilitated by the electrolytic treatment applied to the supernatant. More specifically, we have found that even the small amount of electrolytic treatment required to effectively kill all odor is also sufficient to improve greatly the settleability of the supernatant and to decrease the volume occupied by the supernatant solids. Another very important improvement in the characteristics of the supernatant is a change in color which is brought about by even a small amount of electrolytic treatment. Thus, whereas the supernatant is ordinarily of a dark green to black color, being opaque by reason of the solids entrained therein, we have found that a small amount of electrolytic treatment will bleach the dark solids to a light tan and having a slightly medicinal odor instead of the vile smell ordinarily associated with supernatants.

We have additionally found that such electrolytic treatment of the supernatant by the apparatus of this invention brings about a significant reduction in both its BOD and COD. Moreover, there is a very substantial kill of bacteria, with the amount of bacteria kill being a function of the amount of electrolytic treatment applied.

In addition to treating the supernatant as aforesaid, we have also found that greatly improved operation of the plant can be obtained by treating the final effluent. Where the primary objective is to provide disinfection of the plant effluent, as is the case when the effluent is to be returned to a stream or the like, it is then ordinarily possible merely to treat the effluent by circulating a portion through a side stream which includes an electrolytic hypochlorinator unit. Hypochlorite can efficiently be produced in such a side stream unit and thereby provide a very high degree of bacteria kill in the final effluent returned to the stream. In some instances, it may be desired to use at least a portion of the final effluent for re-use, as for power plant cooling, irrigation, etc. In that event, it may be desired to provide further treatment, over that which is provided by the hypochlorinator; thus, the effluent may be caused to flow through a chamber wherein there are disposed a number of the electrolytic cells of the invention. Each cell generates hypochlorite and also ozone and other oxidative species which are effective to a very substantial degree to disinfect the effluent and to provide it with a substantial chlorine residual. Such further treatment has the additional effect of bleaching and coagulating the suspended solids and decreasing the organic pollutants, thereby clarifying and purifying still further the re-use water which additionally is entirely odorless. Frequently, such further treatment can be accomplished with no addition of chemicals to the system since only a very low

salt concentration is required to permit the desired electrolytic action.

BRIEF DESCRIPTION OF THE DRAWINGS

FIG. 1 is a combination block diagram and flow diagram of a typical sewage system employing anaerobic digesters for the treatment of sludge and electrolytic treatment of the supernatant from such digesters, together with electrolytic production of hypochlorite for disinfection of the final plant effluent and supplementary treatment for re-use;

FIG. 1A is a flow diagram illustrating a modification of a portion of the process illustrated in FIG. 1;

FIG. 1B illustrates a further modification of the process of FIG. 1;

FIG. 1C illustrates schematically a typical hypochlorinator for treatment of re-use water;

FIG. 2 is a cross-sectional view of a typical electrolytic assembly of the kind preferred for use in the method and apparatus of this invention;

FIG. 3 is a view illustrating a plurality of assemblies of the type of FIG. 2;

FIG. 4 graphically shows the relationship between cell amperage and the flow rate of supernatants through a cell for various desired dosages of the supernatant;

FIG. 5 is a flow diagram illustrating still another modification of the process of FIG. 1 wherein all of the output from the digesters including supernatant and sludge is treated by the electrolytic cells;

FIG. 5A schematically illustrates apparatus for the arrangement of electrolytic cells to provide additional water disinfection adequate to permit re-use of the final effluent;

FIG. 6 is a flow diagram of another modification of the process of FIG. 1 wherein the sludge from the primary settlers is fed directly to electrolytic cells for treatment instead of being first treated in digesters;

FIG. 7 graphically illustrates the relationship between chemical oxygen demand and electrical dosage of the supernatant;

FIG. 8 presents in tabular form some of the changes in characteristics of the supernatant after electrical treatment;

FIG. 9 graphically demonstrates the variation in chemical oxygen demand of the effluent for various levels of electrolytic treatment;

FIG. 10 sets forth in tabular form some of the variations in characteristics of the plant effluent in response to electrolytic treatment of said effluent; and

FIG. 11 illustrates graphically the variation in percentage of bacteria kill of the effluent with variations in electrical discharge.

DETAILED DESCRIPTION OF THE PREFERRED EMBODIMENT

FIG. 1 illustrates a very common type of sewage treatment system as modified to incorporate therein the electrolytic treatment of the present invention. Thus, the raw sewage is shown as being subjected first to the treatment of a bar screen 10 which has the function of removing large objects entrained in the sewage and which would otherwise prevent proper treatment of the sewage if not first removed. Following removal of such solid particles by the bar screen, the sewage is conducted to the grit chamber 11 which provides an opportunity for additional heavy solid and suspended articles to settle out. Following this, the sewage is conveyed to the primary settler 12.

The function of settler 12, as is well known, is to permit additional solid matter to float or settle out of the water. The liquid portion, termed the primary effluent, is subjected to further secondary treatment at 13 which may include, for example, the well-known trickle filters. The sludge which settles out of the primary settler 12 is commonly treated in one or more anaerobic digesters 14. In such digesters, the sludge is preferably kept at an elevated temperature to promote the growth of bacteria, and the sludge is maintained in such digesters for a period of

from two to four weeks to provide the required bacteriological digestion of the suspended and colloidal organic material therein. The sludge which settles out of the digesters is ordinarily removed and disposed of by any one of several well-known methods, but the supernatant is generally caused to flow back to the primary settler 12 for further treatment.

As long as the system is treating a quantity of sewage which is within the plant's design limits, and the plant is operating as designed, adequate digestion can take place in the anaerobic digesters 14 with the result that the supernatant can be discharged to the primary settler 12 without undue deleterious effect. However, in the event of a system upset or overload, bacteriological action or residence time in the anaerobic digesters is insufficient to produce an inert or stabilized discharge. The odor of the supernatant under such conditions becomes so vile that it cannot be discharged to the outside atmosphere without creating a serious odor problem. In addition, the only partially digested discharge has a very high Biochemical Oxygen Demand (B.O.D.) which increases the load on the rest of the sewage plant.

One solution to the foregoing problem is to increase the capacity of the anaerobic digesters, but this is a highly expensive undertaking and also requires a considerable amount of time. Many communities have therefore been required to resort to extreme methods including, in many instances, the removal of the supernatant to a remote site in order to bury it. This, in itself, is a most unsatisfactory solution since it does not effectively and safely dispose of the supernatant and besides the mere handling of the supernatant creates real problems because the supernatant under these conditions tends to be a highly putrescent material, contaminated with fecal bacteria and high in organic contaminants.

FIG. 1 illustrates the process and apparatus of this invention for treatment of the supernatant. Thus, the supernatant is pumped from the digesters 14 to a recycle tank 15 where it rapidly mixes with previously treated supernatant. The oxidation species in the already treated fluid react rapidly with odorous compounds, quickly destroying the putrescent odor. The supernatant is caused to recycle by means of a pump 16 through a head tank 17 and then through electrolytic cells 18 back to the recycle tank 15. The head tank 17 has a sufficient height so that, if kept substantially filled, the various electrolytic cells will also remain filled with supernatant as is required for proper cell operation. A brine tank 19 is provided in order that a predetermined minimum concentration of salt can be maintained in the supernatant. While it has been found through experience that the salt (particularly sodium chloride) normally present in the supernatant fluid is enough to give sufficiently high conductivity for the desired electrolytic action, it has also been found that improved performance in the cells 18 can be achieved by addition of salt. A concentration of salt of two grams per liter has been found adequate, although higher concentrations do no harm. In order to provide this concentration, sodium chloride is placed in the brine tank 19 and water is caused to flow therein, and the resulting overflow of the sodium chloride solution then flows through an overflow line 20 to the recycle tank 15. The resulting treated fluid discharge from tank 15 may then be fed back to the primary settler 12.

FIG. 2 illustrates a typical one of the electrolytic assemblies of the type which is preferred for use in connection with this invention. The anode 21 comprises a coating of lead dioxide which is electroplated onto a substrate preferably of graphite or titanium according to the teachings of U.S. Patents 2,945,791 and 3,463,707, both of which are assigned to the assignee of this application. The resulting lead dioxide coating is dense, hard, and impervious even in the presence of highly corrosive electrolytes. Such an anode is very efficient in the conversion of sodium chloride into sodium hypochlorite, even at very low concentrations of sodium chloride. Ozone and

other oxidative species are also produced, making the cell extremely effective in oxidizing contaminants present in the waste water being treated.

The cathode 24 is a metal can which may be of copper, stainless steel, iron, or other suitable metal, and serves the dual function of being both a cathode and a container for the fluids being processed. The can 24 is provided with fluid inlet 26 and fluid outlet 32, thereby providing for the upward passage through the assembly of the fluid being treated. Electrical connections may be made to a source of direct current at 31 for the anode and at 33 for the cathode. While the preferred configuration is as described above, it must be understood that other anode-cathode configurations can also be used. It is, for example, feasible to provide alternate flat anodes and cathodes assembled in sandwich fashion, and other arrangements are also possible.

Multiples of the anode-cathode assemblies of FIG. 2 may be provided as shown schematically in FIG. 3. The number of assemblies selected is dependent upon the power dosage required for the desired treatment and the fluid flow rate. The waste water to be treated enters the conduit 25 and then enters each assembly at its bottom, inlet end, flowing upwardly therein, and through a respective outlet 27 to a common discharge conduit 29. Each may be connected across the electrical supply as shown.

FIG. 1A illustrates a modified form of the process of FIG. 1. In FIG. 1A, the supernatant from the anaerobic digesters is all caused to flow to the head tank 17 and then through the electrolytic cells 18, and with the discharge from such cells being returned to the primary settler 12. In this modification, there is no need to provide the separate recycle tank and head tank 17; however, it must be remembered that flow rate through the cells is dependent on supernatant feed rate and is thus not an independent variable but is instead a function of the plant load, sewage quality, and other factors. Consequently, if all the supernatant is to flow through the electrolytic cells 18, special precautions must be taken to ensure that all the cells are at all times provided with a fluid flow therethrough during cell operation.

A still different modification of the process of FIG. 1 is shown in FIG. 1B. According to this modification, a portion only of the supernatant from the anaerobic digesters is caused to flow into the recycle tank 15. The combination of the recycle tank 15, pump 16, header tank 17, electrolytic cells 18, and brine tank 19 is the same as previously described in connection with FIG. 1. However, in FIG. 1B, only a portion of the supernatant is thus treated, with the remainder of the supernatant being supplied to a separate supernatant treatment tank 30. This treatment tank 30 also receives the discharge from the recycle tank 15, which discharge is overtreated so as to have a high concentration of hypochlorite, substantially in excess of the hypochlorite concentration when the embodiment of FIG. 1 is employed. However, such overtreated supernatant is then mixed with the supernatant directly supplied to tank 30 from the digesters with the result that the untreated supernatant is also subjected to oxidation from the overtreated supernatant. The resulting discharge from treatment tank 30 is then fed back to the primary settler as before.

One advantage of operating in this manner is that the salt concentration in the recycle tank 15 and hence in the electrolytic cell 18 can be increased, thereby increasing the conductivity of the fluid being electrolytically treated and therefore increasing the efficiency of the electrolytic treatment but without increasing the salt concentration in the final treated discharge from tank 30. Another advantage is that in treating sludge or supernatant from two different sources (for example, supernatant and sludge from the anaerobic digester, and sludge from primary and secondary settlers), the two sources providing respectively different solids content, the one which contains less troublesome solids can be fed to the recycle

tank for better operation. Still another advantage is for treating large volumes of fluid containing low solids content since all of the fluid does not need to be increased in salt concentration for efficient treatment.

FIG. 4 illustrates the relationship between the flow rate of supernatant fluid feed to the unit as measured in gallons per minute compared to the cell amperes for different dosage values as measured in kiloamperes per thousand gallons of treated supernatant. As an example, it can be seen from FIG. 4 that, for a supernatant fluid feed of thirty-two gallons per minute, and for a desired dosage of 1.0 kiloampere per thousand gallons of supernatant, the combined cell amperage must be approximately 2000. Similarly, for a fluid feed of supernatant at a level of 40 gallons per minute, and for a desired dosage of 4.0 kiloamperes per thousand gallons, it can be seen that the combined cell amperage must be adjusted to about 9400 amperes.

The shaded area of the graph of FIG. 4 illustrates the desired operating range for effecting the desired treatment of the supernatant in accordance with the process of FIGS. 1, 1A, and 1B. As a further example, assuming that the rate of supernatant flow is at about 32 gallons per minute, one can see from FIG. 4 that the desired cell amperage to stay within the shaded area of the graph extends from approximately 3600 amperes to 9800 amperes, and that this magnitude of cell amperage will provide a dosage of the supernatant extending from somewhat less than 2.0 kiloamperes per thousand gallons for the lower current level to a level in excess of 5 kiloamperes hours per thousand gallons. The lower level of current dosage for the cells is the minimum level at which the odor of the supernatant is destroyed. The upper level of dosage as computed in accordance with FIG. 4 is approximately the level beyond which increased treatment will result in a sufficient bacteria kill to result in a substantial reduction in the bacterial action taking place within the system.

FIG. 7 illustrates graphically the relationship between the amount of electrical dosage applied to the supernatant and the reduction in chemical oxygen demand of the supernatant. Thus, in a typical situation, the supernatant prior to any electrolytic treatment may have an oxygen demand in excess of 13,000 milligrams per liter, but even a relatively small amount of electrolytic treatment of, for example, less than two kiloampere hours per thousand gallons results in a reduction in oxygen demand to a level of less than 11,000 milligrams per liter. FIG. 7 shows that the oxygen demand decreases with increasing electrical dosage, and becomes less than half of the original value when the electrical dosage is somewhat in excess of 20 kiloampere hours per thousand gallons. Of course, such a high electrical dosage is often not practical, but even the substantially lower reduction in oxygen demand, in the order of 10-25% which results with an electrical dosage not exceeding five kiloampere hours per thousand gallons is very beneficial in the overall plant operation.

FIG. 8 illustrates in tabular form some of the additional changes in the characteristics of the supernatant following electrolytic treatment. Thus, it is shown that for even relatively moderate dosages, i.e. a cell current of between 1 to 4 kiloampere hours per thousand gallons, the chlorine in the form of sodium chloride is decreased, the residual chlorine is increased and may be in the range of zero to 30 parts per million dependent upon the amount of the current dosage, both the C.O.D. and B.O.D. are reduced, the C.O.D. being reduced from 10-25% and the B.O.D. from 15-30%, the putrid septic odor is completely eliminated so that the supernatant is left with a slightly medicinal odor, and the color is transformed from a virtual black to a light tan color. In addition, both volatiles and phosphates are significantly reduced, volatiles being reduced from 3-11% and the phosphates from 2-15%, and ammonium nitrogen is also reduced.

A further modification of the invention is illustrated

in FIG. 5. According to FIG. 5, the electrolytic cells 18 receive both the supernatant and the sludge from the anaerobic digesters 14. This type of operation is practical only where the mechanical separation of solids from the sewage is sufficiently effective to ensure that all large particles are removed since it will be apparent that under these circumstances all of the fluid discharge from the digesters, including the sludge, is required to flow through the cells, and the rather limited anode-cathode spacing will not permit the introduction of large solid matter into the cells.

FIG. 5 further illustrates that the outflow from the cells 18 is caused to flow to drying beds or lagoons and that preferably two or more such drying beds or lagoons are employed. The cell outflow is first caused to flow to one of the drying beds and with the overflow therefrom being returned to the primary settler 12. In such drying bed, the solids tend to settle out, and when the maximum amount of solids has accumulated on the bottom, the outflow from the cells 18 is diverted to the other drying bed, with the settled-out sludge then being permitted to dry in the first bed and being thereafter removed and disposed of in any desired manner.

In employing the modification of FIG. 5, it is desired that the electrolytic dosage be at the higher end of the scale, i.e. at the upper end of the shaded area of FIG. 4.

A still further embodiment of the invention is shown in FIG. 6. In this embodiment, anaerobic digesters are not employed and instead the sludge which settles out in the primary settler 12 is applied directly to the electrolytic cells. Here, again, as in connection with FIG. 5, it is important that all large solids be first removed so that they will not tend to clog the cells. Also, as was described in connection with FIG. 5, alternately-used drying beds or lagoons are employed for receiving the effluent from the electrolytic cells. The overflow from the drying beds or lagoons is returned to the primary settler as shown, and the mixture of this return flow and the raw sewage may, of course, after passing through the primary settler, be given any of various kinds of secondary treatment as is well-known in the art including, for example, the common trickle filters as already described in connection with FIG. 1.

FIG. 1 illustrates not only the electrolytic treatment of the supernatant from the anaerobic digesters 14, but also shows that the effluent from the secondary treatment at 13 may also be subjected to electrolytic treatment. Preferably, an electrolytic hypochlorinator 36 which also makes use of the electrolytic cells as described herein is employed to treat a side stream portion of the effluent; in some instances, as, for example, when the effluent is extremely hard, it may be preferable to feed fresh water or even softened water to the hypochlorinator to avoid the deposition of scale in the apparatus. The hypochlorinator may comprise a brine tank from which an overflow having a high concentration of sodium chloride discharges to a recycle tank 38 as in FIG. 1C. The solution in the recycle tank 38 is continuously pumped by pump 40 through cell 18 and then through heat exchanger 39 and finally back to tank 38, with the overflow from tank 38 discharging to the stream to be treated. The function of heat exchanger 39 is to prevent a build-up of heat in the electrolyte as a result of the cell action which would form reactions tending to produce chlorates instead of hypochlorite; preferably the electrolyte is maintained at a temperature not exceeding 37° C.

At times, it is desired that at least a portion of the plant effluent be made available for re-use. In that event, additional treatment may be required over and above that provided by the side-stream electrolytic hypochlorinator 36. This may be provided by causing the entire effluent which is to receive such further treatment to flow through an assemblage of the cells 18 as shown in FIG. 5A.

FIG. 9 illustrates graphically the relationship between chemical oxygen demand of the plant effluent and the

amount of electrical dosage of the effluent, and it can be seen that even a modest electrical dosage of somewhat in excess of one kiloampere hour per thousand gallons will result in a reduction of C.O.D. from a level in excess of 70 milligrams per liter to a value less than 50 milligrams per liter, with increasing electrical dosage resulting in even lower values of C.O.D.

above. The current in the unit was 1800 amperes, the voltage was 13.0 volts, the effluent feed rate was 8.4 gallons per minute, and the salt connection was 1.0 gram per liter. Samples of the supernatant were tested after passage through one, three, and finally all five assemblies of each bank.

The following results were noted:

	Before treatment	After treatment		
		1 cell	3 cells	5 cells
Residual chlorine, p.p.m.		0.0	0.0	0.33
COD, mg./l.	13,800	11,900	11,100	11,300
Bacteria count, No./ml.	17,400	15,000	7,500	430
pH	6.3	6.1	6.1	5.7
Odor	Putrid	Mildly putrid	Medicinal	Medicinal
Color	Dark opaque	Brown	Light brown	Light brown

Additional advantages resulting from the electrolytic treatment of the effluent are set forth in tabular form in FIG. 10. The most notable results are the increase in residual chlorine coming about from even a very small current dosage of approximately one-third of a kiloampere hour per thousand gallons producing a residual chlorine of 5 to 10 parts per million, and a reduction in bacteria from a value of greater than 10,000 to less than 100.

FIG. 11 shows graphically the relationship between bacteria kill and electrical dosage, illustrating clearly that even very small amounts of electrical dosage bring about a high percentage of bacteria kill.

SUPERNATANT TREATMENT

Example 1

The supernatant treatment unit was operated in accordance with the diagram of FIG. 1. The electrolytic cells included 40 anode-cathode assemblies each comprising an anode having a coating of lead dioxide on a substrate of graphite and a cylindrical copper can as a cathode. Supernatant flow was through all of the assemblies in parallel. Electrically, the forty anode-cathode assemblies were connected in two groups of twenty anode-cathode assemblies in parallel. The two groups, or cells, were connected in series. The current through each cell was 5000 amperes, and the voltage of each cell was 16 volts. The feed rate of the effluent from the digester 14 into recycle tank 15 (FIG. 1) was 38 gallons per minute, and the salt concentration in the recycle tank was maintained at 1.7 grams per liter. Each anode had an outside diameter of 4.125 inches, and an overall length of 45 inches, 4 $\frac{1}{4}$ inches at the upper end being uncoated and extending exteriorly of the surrounding cylindrical cathode can to permit the making of electrical connections to the anode. The cathode can was formed of copper and had an inside diameter of 4.5 inches.

	Before	After
Odor	Septic-putrid	Slightly medicinal
Color	Greenish-black	Light brown
Turbidity	Opaque	Less turbid
COD mg./l.	12,070	9,430
Percent volatile solids	64.5	59.6
pH	6.7	6.9

In addition, the suspended solids settled more rapidly and occupied less volume after treatment than before.

Example 2

A supernatant treatment unit was operated essentially as shown in FIG. 1A, with the supernatant being fed directly to the electrolytic cell, and the discharge from such cell being returned directly to the primary settler. Ten individual anode-cathode assemblies were employed in two separate banks, with the five assemblies in each bank being electrically connected in parallel. Flow of the supernatant was through all the anode-cathode assemblies of each bank in series. Each anode-cathode assembly was of the type described in connection with Example 1

Example 3

Operation of the unit was as shown in FIG. 1, using the anode-cathode assemblies as described in Example 1, except that 10 anode-cathode assemblies grouped in 1 cell, was made to discharge the treated fluid from the cell to a foam disengagement chamber which consisted of a 20-inch diameter pipe with a foam discharge spout 6 inches above the liquid level. Liquid discharged from the bottom of the foam disengagement chamber and foam discharged from the top. This utilization of physical separation of solids in the foam by flotation of solids is effective in removing additional organic matter from the supernatant. The cell amperage was 1830 amperes, the cell voltage was 13.0 volts, the supernatant feed rate 10 gallons per minute, and the recycle rate was 50 gallons per minute. The salt concentration was maintained at 1.6 grams per liter. The following results were noted:

	Before treatment	After treatment	
		Putrid	Medicinal
Odor		Putrid	Medicinal
Color		Black opaque	Light brown
COD, mg./l.	13,500	10,100	10,100
BOD, mg./l.	9,120	8,380	8,380
Volatile solids, percent	62.5	43.5	43.5

Settling characteristics of the solids were improved.

HYPOCHLORINATION UNIT

Example 4

A hypochlorination unit as shown in FIG. 1C was operated to produce hypochlorite electrolytically from a brine solution. Salt was placed in the brine tank and water fed to the bottom of the salt bed. The brine approached saturation before overflow from the brine tank to the recycle tank, and thereafter additional water was fed to the recycle tank at a rate to maintain the salt concentration at a predetermined level. The brine solution is continually recycled from the recycle tank to the electrolytic cells and back to the recycle tank.

The electrolytic cells included 20 anode-cathode assemblies, each the same as described in Example 1 above and grouped in cells of 10. The flow rate and average residence time of the fluid in the cells was selected to produce hypochlorite at a predetermined level for disinfection of the effluent discharge from the sanitation plant in accordance with the results presented in tabular form below. The hypochlorite solution thus prepared was either used directly to treat the effluent or was pumped to a storage tank for later use to treat the effluent during peak periods. The following results were observed:

Overflow rate from unit (gal./min.)	NaCl, g./l.	Cl ₂ , g./l.	Percent conversion	
			C.E. to Cl ₂	Cl ₂ to ClO ₂
6.0	9.4	3.95	50.4	40.8
6.67	10.6	3.79	57.6	37.0
3.43	13.7	6.16	45.7	42.5
5.76	17.2	6.44	51.7	38.0

11

RE-USE UNIT

Example 5

The re-use treatment unit is operated in the manner generally shown in FIG. 5A, employing altogether 104 anode-cathode assemblies arranged in four cells as shown in FIG. 5A, with 26 anode-cathode assemblies in each of the cells. Each of these anode-cathode assemblies was of the type described in connection with Example 1 above. The 26 anode-cathode assemblies in each major cell was electrically connected in parallel across the power source, and each assembly was also connected in parallel from the viewpoint of solution flow. The four major cells were electrically connected in series. The actual flow through the overall unit was approximately 3,000,000 gallons per day. Average voltage was 58 volts and cell amperage was 3440 amperes. The following results were observed:

	Before treatment	After treatment
Chloride concentration, mg./l.	265	6.4
Residual Cl ₂ , p.p.m.	0.2	0
Chlorine demand, p.p.m. (break point)	4.6	0
COD, mg./l.	73	66
BOD, mg./l.	16.1	5.6
E. coli, MPN/100 ml.	5,160	1.7
pH	7.4	7.2

Example 6

Ten anode-cathode assemblies were used, connected in two banks each including five assemblies. Each assembly was of the type described in Example 1 above. The water thereby treated was pumped to a head tank and then from the head tank through the two banks of cells in series. Electrical connection was in parallel for all the assemblies. The cascade flow through the five assemblies in series of each bank permitted sampling after any one of the five, with each of the five assemblies receiving essentially the same electrical dosage. The flow rate was 2.2 gallons per minute, the cell voltage was 14.2 volts, and cell amperage was 750 amperes. The following results were observed:

	After treatment through, assemblies—				
	Before	1	2	3	4
Chloride, mg./l.	257	237	225	202	181
Residual chlorine, p.p.m.	0	23	27	82	120
COD, mg./l.	75	60	—	—	42
BOD, mg./l.	15	—	—	5	—
Bacteria count, No./ml.	*TNC	34	—	5	—
pH	7.2	6.7	—	—	7.0

* TNC=(Too numerous to count).

The above test was repeated, but with a higher flow rate and a higher cell amperage. More specifically, the flow rate was 10 gallons per minute and the cell amperage was 900 amperes, with the cell voltage equalling 14 volts. Under these conditions, the following results were obtained:

	After treatment through, assemblies—				
	Before	1	2	3	4
Chloride mg./l.	341	331	325	312	317
Residual chlorine, p.p.m.	0	13	23	30	22
COD, mg./l.	80	82	78	68	71
BOD, mg./l.	24	0.6	2.4	1.8	0
Bacteria count, No./ml.	TNC	—	0	0	0
pH	7.0	7.2	7.1	7.0	7.1
Dissolved oxygen, mg./l.	3	9	11	13	13

What is claimed is:

1. In a process for the treatment of a stream of waste water containing malodorous compounds and/or other rapidly oxidizable components which includes at least one biological treatment step, the improvement which comprises the step of electrolytically treating at least a portion of the stream in a cell having electrochemically stable electrodes and with an electrode current density sufficiently high to produce bactericidal products which

12

quickly oxidize the malodorous compounds and/or rapidly oxidizable components, and the further step of returning at least a part of the thus electrolytically treated portion to the stream upstream of the place where such biological treatment step is effected.

2. The process of claim 1 wherein the sodium chloride concentration of the liquid in said electrolytic cell is maintained at about at least two grams per liter.

3. The process of claim 1 wherein the cell cathode comprises a hollow metal tubular can and the cell anode comprises a circular rod concentrically positioned within but electrically insulated from said cathode can.

4. The process of claim 3 in which said liquid in said electrolytic cell is caused to flow upwardly in said cell in the annular anode-cathode spacing, said cell being so positioned that said tubular cathode can is substantially vertical.

5. The process of claim 12 in which the relationship between the cell amperage and the flow rate of supernatant being treated in such as to lie within the shaded area of the graph of FIG. 4.

6. The process of claim 12 in which the supernatant from the anaerobic digester is transported to a recycle tank, and the liquid in the recycle tank which comprises supernatant mixed with electrolyzed supernatant is continuously recycled through said electrolytic cells.

7. The process of claim 6 in which brine is added to said recycle tank to maintain the salt concentration in said recycle tank at about two grams per liter.

8. The process of claim 12 in which the supernatant from the anaerobic digesters is transported through said electrolytic cells and thence directly to said primary settler.

9. The process of claim 12 in which the supernatant from the anaerobic digester is transported through said electrolytic cell and then to drying beds, and the overflow from said drying beds is returned to said primary settler.

10. The process of claim 12 in which a portion of the supernatant is transported to a recycle tank and a portion is transported to a treatment tank, the supernatant in the recycle tank is continuously circulated through said cell and back to said recycle tank and the overflow from said recycle tank is transported to said treatment tank.

11. The process of claim 10 in which the treated fluid which is discharged from said treatment tank is discharged to said primary settler.

12. The process of claim 1 wherein the portion of the stream which is electrolytically treated comprises the supernatant from an anaerobic digester receiving the sludge from a primary settler,

said electrolytically treated part of the sewage stream being returned to said primary settler.

13. The process of claim 12 wherein the supernatant from the anaerobic digester is circulated through a loop including a recycle tank and at least one electrolytic assembly,

the overflow of said recycle tank being transported to said primary settler.

14. The process of claim 1 in which said electrolysis takes place in an electrolytic assembly comprising an anode formed of a dense hard coating of lead dioxide on a substrate.

15. A process for the treatment of sewage comprising the steps of:

settling the sludge from the incoming sewage stream in a primary settler,

electrolytically treating at least a part of the sludge from the primary settler in a cell having an anode and a cathode which are energized from a direct-current source and in which the sodium chloride concentration of the cell electrolyte is maintained at at least about two grams per liter, the anode being formed of an electrochemically stable material and the current density of the cell electrodes being sufficiently high to produce bactericidal agents which

13

quickly react with the rapidly oxidizable components of the sewage, returning the electrolytically treated effluent to the sewage stream, and biologically treating the sewage stream downstream of the location at which the electrolytically treated effluent is returned to the stream.

16. A process for the treatment of sewage comprising the steps of:

screening from the raw sewage substantially all large solid particles, transporting the screened sewage to a primary settler, allowing smaller solid particles to settle out in said primary settler as sludge, flowing said sludge through at least one electrolytic cell comprising a metal cathode and an anode having an exterior coating of lead dioxide, transporting the discharge from said cell to a lagoon, conveying the overflow from said lagoon to said primary settler, and biologically treating the mixture of treated effluent and raw sewage from said primary settler.

17. A process for the treatment of sewage in a treatment plant having a primary settler and an anaerobic digester for digesting comprising the steps of, conveying both the sludge and the supernatant from

5

20

25

14

the anaerobic digester to at least one electrolytic cell having at least one anode and one cathode respectively connected to the opposite terminals of a direct-current source, thereafter transporting the discharge from said electrolytic cell to a lagoon, conveying the overflow from said lagoon back to said primary settler, and biologically treating the effluent from said primary settler.
